UNITED STATES PATENT OFFICE.

JAMES E. GLEASON, OF ROCHESTER, NEW YORK, ASSIGNOR TO GLEASON WORKS, OF ROCHESTER, NEW YORK, A CORPORATION OF NEW YORK.

CUTTER-GRINDING MACHINE.

1,285,124.

Specification of Letters Patent. Patented Nov. 19, 1918.

Application filed September 15, 1916. Serial No. 120,238.

To all whom it may concern:

Be it known that I, JAMES E. GLEASON, of Rochester, in the county of Monroe and State of New York, have invented certain new and useful Improvements in Cutter-Grinding Machines; and I do hereby declare the following to be a full, clear, and exact description of the same, reference being had to the accompanying drawings, forming a part of this specification, and to the reference characters marked thereon.

My invention has for its purpose to provide a cutter grinding apparatus designed more particularly with a view to finishing the surfaces of certain types of cutter blades, such for instance as are employed in the production of curved tooth gears formed on the arc of circles, spirals, roulettes or other selected curve. More particularly the invention is designed with a view to imparting a relieving motion to the grinding members so as to afford the necessary clearance for the blade when in cutting engagement with a blank. An additional object of the improvement is to provide a mechanism upon which cutter blades of the character mentioned can be ground and finished accurately and expeditiously. To these and other ends the invention consists in certain improvements and combinations of parts all as will be hereinafter more fully described, the novel features being pointed out in the claims at the end of the specification.

In the drawings:

Figure 1 is a plan view of an apparatus constructed in accordance with the invention in its preferred embodiment;

Fig. 2 is a diagrammatic view illustrating the relative positions of the grinding members and cutter at the commencement of each grinding operation;

Fig. 3 is a similar view showing the relative positions of the same parts at the end of each grinding operation;

Fig. 4 is a side elevation of the cutter with the operating surfaces of the grinding members in grinding relation;

Fig. 5 is a perspective view of one of the blades that may be ground upon the apparatus;

Fig. 6 is a vertical sectional view taken centrally of the cutter;

Fig. 7 is a side elevation of the machine;

Fig. 8 is a sectional view on line 8^a—8^a of Fig. 6;

Fig. 9 is a sectional view on line 9^a—9^a of Fig. 6;

Fig. 10 is a view in elevation looking toward the left side of the parts shown in Fig. 9;

Fig. 11 is a sectional view on the line 11^a—11^a of Fig. 1;

Fig. 12 is a sectional view on line 12^a—12^a of Fig. 11;

Fig. 13 is a sectional view on line 13^a—13^a of Fig. 1; and

Fig. 14 is a vertical sectional view on line 14^a—14^a of Fig. 1.

Similar reference characters throughout the several views indicate the same parts.

In the present embodiment, 1 designates the main frame provided with standards 2 forming a bearing for a spindle or cutter support 3, the cutter being mounted upon the inner end of the latter and embodying a head 4 and a series of blades 5. The spindle 3 carries at its outer end a worm gear 6 driven by a worm 7 which is mounted upon a shaft 8. The latter carries a gear 9 at one end, which engages a coöperating gear 10 fixed upon the shaft 11, carrying a pulley 12, to which power is supplied through a belt 13 from a main drive shaft 14.

The structure which has thus far been described constitutes a means for rotating the cutter continuously during the grinding operation, the cutter being turned so as to initially present the cutting edges of the blades to the grinding members, or in other words, the blades are moved in the same direction as when they are in cutting operation upon a blank.

The cutting portion of each blade, which is shown in detail, is curved from front to back on a suitable arc, and is relieved upon its outer end and side walls to permit proper clearance as it travels through a tooth space, and in order to finish the surfaces referred to with the proper

contour, a relieving motion is imparted to the grinding members during each grinding operation, that is to say, each grinding member is given a movement bodily in the direction of the axis of the cutter support and toward the latter. To this end, the several grinding members which will be more fully described presently are mounted upon a main bed 15 that is slidable back and forth on the base by the mechanism now to be described. The bed 15 carries at one end a pin

100

110

or projection 16 engaging a cam slot 17 in the cam disk 18. The latter is fixedly mounted upon an arbor 19 carrying a worm wheel 20 that is driven by the worm 21 mounted upon the shaft 11 already referred to. It will be seen that from the gearing just described, the cam 18 is continuously rotated, and through the slot 17, imparts a reciprocatory movement to the main bed 15. The 10 contour of the slot 17 is such, as appears in Fig. 1, as to impart a slow feeding-in movement of the bed, and a quick return, or in other words, the grinding members are given a relatively slow relieving motion toward 15 the back end of each cutting portion during the grinding operation and a quick return movement to bring the grinding members back to proper position for cooperation with the blades next presented. Three grinding 20 members are preferably provided formed of emery, carborundum, or similar substance, one operating upon each side face of a cutting portion of a blade, and a third one upon the outer end of the blade. In the present 25 arrangement, grinder A engages the inside face *a* of each cutting portion, grinder B engages the outside face *b* of each cutting portion, and grinder C is of hollow annular formation with its edge in engagement with 30 the outer end *c* of a cutting portion. Each grinding member is mounted upon a spindle as illustrated by 18^a, which carries at its opposite end a pulley 19^a adapted to receive a belt for driving the grinding wheel. The 35 grinding element C and its spindle are journaled in bearings secured upon a standard 20^a carried by the main bed 15 and is adjustable toward and from the cutter for preliminary positioning by a threaded adjusting stem 21^a. Each of the remaining grinding 40 elements is mounted upon the bed for both lateral and angular adjustment with reference to the cutter, such adjustment being obtained in the following manner: Each 45 grinding wheel spindle is mounted in bearings upon a standard 22, adjustable laterally upon a slide 23 through the instrumentality of an adjusting screw 24 carried by the standard and nut 25 fixed on slide 23. The 50 slide 23 is adjustable in a direction at right angles to the screw 24, on a supplemental bed 26 and carries a toothed rack 27 engaged by a pinion 28, and by turning the latter, the support 23 may be moved back and forth 55 upon the supplemental bed 26. The pinion 28 is mounted on an arbor 29 carrying an operating handle 30 at its upper end. The handle 30 is pivoted at 31 to an ear 32 and is held at any desired position of adjustment 60 by the projections 33. The supplemental bed 26 is pivoted upon the main bed 15 to swing about the axis 34, and is adjusted by means of a worm 35 having engagement with a rack 36. The bed 15 carries a toothed 65 rack 37 engaging a pinion 38 upon a spindle,

provided with a hand wheel 39 and when it is desired to adjust the bed manually away from the cutter, the pin 16 is removed and by turning the wheel 39 the bed and grinding members can be moved to any position. 70

By the several adjustments already described, each grinding member can be moved with relation to the main bed 15 until it is in the proper location relatively to the cutter head. Preferably, the grinding members 75 are arranged in the angular relation shown, the grinding wheel C being located with its grinding edge parallel to the outer end of the blade to be ground, and grinding wheels A and B being located at angles corresponding to the angles of the outside and inside surfaces of the cutting portion of the blade. In operation, the several grinding members are rotated continuously and at the same time the bed 15 is moved back and 80 forth in the direction of the axis of the cutter head, producing corresponding movement of the grinding members so that they are moved bodily toward the base of each blade during the cutting operation and while 85 the blade is presented to the grinding member with its cutting edge first. In other words, the movement of the grinding wheels bodily back and forth is so tuned with reference to the rotation of the cutter head, that 90 the grinding wheels are in their outer positions as they engage the outermost part of the blades and as the blade moves along through rotation of the cutter head, the grinding wheels are moved bodily through 95 the longitudinal movement of the bed 15 at such a rate as to correspond to the angle of relief of each blade. This imparts a relieving motion to the grinding wheels which grinds the outer end and opposite sides of 100 each blade accurately, and exactly according to the predetermined angle of relief. The three grinding members may be used simultaneously, or if desired, they can be operated one at a time to finish the sides and 105 outer end of the blade one at a time, although this does not affect the principle of operation of the apparatus as the relative motion of the cutter head and bed 15, which 110 imparts relieving motion to the grinding 115 element is the same, whether one or all of the grinders are in operation.

I claim as my invention:

1. A grinding machine including a cutter blade support, and a plurality of grinding 12 members engaging the sides and outer end of the blade and having a relieving motion with reference to the path of the blade during the grinding operation.

2. A grinding machine including a rotary 12 cutter blade support, a plurality of grinding members engaging an end and both sides of the blade, and a bed on which the grinding members are located having movement in the direction of the axis of the cutter sup-

port and toward the latter during the grinding operation to relieve said surfaces of the blade with reference to the path of its cutting edge.

5 3. A grinding machine including a rotatable cutter blade support, a reciprocatory tool support movable axially of the blade support and a rotary grinding tool thereon, in combination with a driving mechanism 10 connection between it and the blade support for rotating the latter continuously, and independent connections between the driving mechanism and the tool support for reciprocating the latter a predetermined number of 15 times during a single rotation of the blade support.

4. In a grinding machine the combination 20 with a rotary work support and a driving mechanism; of a frame, a plurality of separate rotary grinding members adjustably mounted on said frame, connections between the driving mechanism and the frame and work support for rotating the latter continuously and operating the frame and work 25 support relatively axially of the latter at regular intervals.

5. In a grinding machine the combination 30 with a rotary work support and a driving mechanism, of a reciprocatory frame movable axially of the arbor, connections between the driving mechanism, and the work

support for rotating it continuously, and between it and the frame for reciprocating the latter axially of the work support at regular intervals, and a plurality of rotary 35 grinding members pivotally mounted and separately adjustable upon the frame.

6. In a grinding machine the combination with the main frame and a rotary work support thereon, of a reciprocatory frame, a 40 plurality of rotary grinding members mounted in frames pivoted on the reciprocatory frame and separately adjustable on their pivots, and driving mechanism connected to the work support and reciprocatory frame for continuously rotating the work support and reciprocating the frame 45 axially of the work support at regular intervals.

7. In a grinding machine the combination 50 with the main frame, a rotary work support thereon and a reciprocatory frame guided on the main frame to move axially of the work support, of a plurality of rotary grinding members mounted in frames 55 adjustable on the reciprocatory frame, a rotary shaft mounted in the main frame connected to the reciprocatory frame to move it at regular intervals and connections between said shaft and the work support to rotate it continuously.

JAMES E. GLEASON.
